JOHN THOMAS GREEN, OF DETROIT, MICHIGAN, ASSIGNOR TO GENERAL MOTORS CORPORATION, OF DETROIT, MICHIGAN, A CORPORATION OF DELAWARE

STRIPING FIXTURE

Application filed October 6, 1928. Serial No. 310,870.

This invention relates to the art of painting ornamental stripes. In such work as the painting of automobile bodies an ornamental stripe is commonly employed for decorative effect, the stripe usually being done with a hand brush which requires the exercise of a high degree of skill to secure uniform and properly positioned lines. Hand striping is slow, tedious, and extremely costly.

It is now proposed to avoid hand striping as far as possible and to use instead a striping tool or instrument which in the hands of the ordinary person without special training may be manipulated to discharge a steady flow of striping material onto the work. To aid the workman in his use of the tool a fixture or template is used to serve as a guide. In practice it has been found that the start and finish of a stripe laid down by a tool guided along the template is not as perfect as the remaining portion of the strip and this is attributed to the theory that the flow of striping material at such times is not a steady one and the lines, therefore, are of varying width and shade in accordance with the varying amount of material delivered to the surface. As a remedy for these conditions the present invention contemplates the use of a small plate in association with the guiding edge of the template at both the start and finish of the stripe, which will cover the work and shield it from the application of the striping material at such times when the flow is increasing or decreasing in value. Thus when the amount of material discharged is undergoing a change in value the deposit will be on the plate rather than on the work itself and during such times as when the striping material is being laid down on the work it will be in a steady flow so as to assure an even line from end to end.

The invention will be more clearly understood upon reference to the accompanying drawing illustrating a preferred but not necessarily the only embodiment thereof and in which drawing Fig. 1 is a side elevation of a portion of an automobile body with the template mounted in a window opening.

Fig. 2 is a sectional view taken on line 2—2 of Fig. 1. Fig. 3 is a detail perspective view of the shield.

In the drawing the reference character 1 indicates an automobile body having a window opening in which is positioned a fixture consisting of a rectangular frame 2 formed of short lengths of wood and carrying a series of strips 3—3 preferably of sheet metal which provide the guiding edge for the tool as it is moved around the fixture to apply a stripe bordering the window opening. The fixture may be detachably held in position by any suitable means, as for example the latches 4 pivoted on the frame 2 and which may be swung behind the sheet metal paneling of the body 1. The start and finish of the stripe will be at the lower ends of the vertical strips 3 and at these points there are secured to the strips 5 having a long leg 6 provided with openings 7 for attachment with the strip 3 and a short leg 8 bent inwardly so as to lie closely adjacent to the surface of the work. When a stripe is to be made, the striping tool is positioned over the fixture along the guiding edge so that the discharge portion of the tool is over the plate 5. As the flow of striping material commences, the discharge will be received upon the shorter leg 8 of one of the plates 3, and by the time the end of the leg is reached the flow will have become steady so as to deposit upon the work a uniform stripe until the opposite end is reached, when the applying portion of the tool passes over the shorter leg of the other plate 3 at which time the flow is again cut off and the striping material discharged at a varying rate is deposited upon the plate. From the above description it will be apparent that the plate shields and protects the work from the application of the striping material at all times when the value of the discharge is undergoing a change. Thus a line may be made which is uniform and of even width throughout.

I claim:

1. In a striping fixture adapted to guide a striping tool over the work, a protective shield offset with respect to the guiding por-

tion of the fixture to overlie the work at a predetermined point and over which the stripe applying portion of the tool may be passed prior to its passage over the work.

- 5 2. In a fixture for guiding a striping tool over the work, a protective shield to overlie and protect the work from the stripe applying portion of the tool at the beginning or end of the striping operation.
- 10 3. In association with a template for guiding a device that applies a stripe upon work, means at the guiding edge of the template defining the start of the stripe and on which the striping material may be laid prior to the application of the stripe on the work.
- 15 4. In association with a template for guiding a device that applies a stripe upon work, a shield at an end of the guiding edge of the template adapted to cover the work and receive the striping material laid down by said device as it moves along the guiding edge and over the shield.
- 20 5. In association with a template for guiding a device that applies a stripe on the work, a shield projecting laterally from the guiding edge of the template to cover the work and receive striping material laid down by the device when the device moves thereover and along the guiding edge.
- 25 6. In association with a template for guiding a device for applying a stripe on the work, a shield defining the end of the stripe and adapted to protect the work from the deposit of striping material when the device moves beyond the point where the stripe is to end.
- 30 7. For use in conjunction with a device for applying a stripe upon the work, a template for guiding the device over the work, shields projecting laterally from the guiding edge of the template to cover the work and define the ends of the stripe and to receive the striping material laid down by the device beyond said ends.
- 35 45 In testimony whereof I affix my signature.
JOHN THOMAS GREEN.
